Inventor,
Sylvester L. Tracy,

United States Patent Office.

SYLVESTER L. TRACY, OF CLEVELAND, OHIO, ASSIGNOR TO HIMSELF
AND HENRY MERRITT, OF SAME PLACE.

Letters Patent No. 66,652, dated July 9, 1867.

IMPROVED TOOL.

The Schedule referred to in these Letters Patent and making part of the same.

TO ALL WHOM IT MAY CONCERN:

Be it known that I, SYLVESTER L. TRACY, of Cleveland, county of Cuyahoga, in the State of Ohio, have invented a new and improved Combination-Wrench; and I do hereby declare that the following is a full and exact description thereof, reference being had to the accompanying drawings and to the letters of reference marked thereon.

Figure 1 is a perspective view of the combined implement.

Figure 2 represents one-half the implement, comprising half the wrench-head, the jointed half of the vise and hammer.

Figure 3 is the same view reversed, showing the groove.

Figure 4 represents the other half or mate of the implement.

Figure 5 is the same view, reverse side, with groove.

Figure 6 is the adjustable jaw of the wrench-head.

Figure 7 is the screw-driver.

This improvement consists in combining in one implement an adjustable wrench, a vise, a screw-driver, and a hammer of convenient form, and possessing economy, utility, and efficiency.

I make the handle A in two parts or halves, figs. 2 and 4, each having a groove, B, in the inside, and an opening, O, figs. 3 and 5. They are held together by screws or rivets *a a*. On one end of this handle I make an adjustable wrench, D, and on the other a vise, E. In the groove B there is a screw-driver, C, which is provided with a screw, *i*, and nut, *j*; the nut *j* is round, fills the opening O, and is corrugated on the circumference, and is used to propel the screw-driver in and out when desired. One jaw, D', of the wrench-head D is fixed, and has a diagonal groove, F, in which there is a stationary nut, *f*; the adjustable jaw D'', fig. 6, is provided with a thumb-set screw, *b*, which works in the nut *f*; the jaw also slides in the rabbets *e e*, for the purpose of giving the wrench sufficient strength. The vise E has one-half hinged at *e*, and is provided with a screw, *g*, to give the grip. C is the screw-driver, fig. 7, and may have a slot in it which would permit the screw *g* to pass through, and allow the screw-driver to pass out each side of the screw *g*, or it might pass by the screw *g* on one side. When the screw-driver is extended for use the jaws of the vise may be closed upon it, thus giving it sufficient strength. H is a claw-hammer, and is a part of the wrench-head D. This implement may be cast iron, malleable, and of different sizes.

An improved implement, constructed in the manner above described, combines several essential qualities, chief among which is economy, also utility and durability, embracing in its construction a variety of tools required daily by the artisan and farmer. The wrench being adjustable, is capable of being employed to turn a large range of screw-nuts and bolts. The vise is also applicable to a great variety of uses for which a small vise and pincers are frequently required; the screw-driver and hammer also rendering it of great utility for the purposes for which these tools are constantly needed.

What I claim as my improvement, and desire to secure by Letters Patent, is—

I claim the improved implement herein described as a new article of manufacture.

SYLVESTER L. TRACY.
